UNITED STATES PATENT OFFICE.

MARTIN J. HAHRE, OF PRINCE RUPERT, BRITISH COLUMBIA, CANADA.

MOVABLE SHIELD.

1,261,518.

Specification of Letters Patent. Patented Apr. 2, 1918.

Application filed August 13, 1915. Serial No. 45,346.

To all whom it may concern:

Be it known that I, MARTIN J. HAHRE, a citizen of Norway, residing at Prince Rupert, in the Province of British Columbia 5 and Dominion of Canada, have invented certain new and useful Improvements in Movable Shields, of which the following is a specification.

This invention relates to a new and improved shield of a type designed to afford protection against rifle bullets and shrapnel; and the principal object of the invention is to provide a novel shield of this character that may be readily moved either 15 forwardly or rearwardly and yet quickly secured in a stationary position, thus rendering it more capable of withstanding the terrific impact of missiles striking thereagainst.

Another object of this invention is to provide an improved shield that is fully protective and which is provided with a series 20 of loop-holes, through which the occupants may fire. However, the said loop-holes may 25 be normally closed through the instrumentality of a series of hinged tampions or the like so as to prevent the entrance of the flying missiles during the movement of the shield or at the time the occupants are re- 30 loading their rifles.

A further object of this invention is to provide improved means which afford facilities 35 for moving the shield from place to place, the said means being in the form of a handle structure that may be easily grasped by the operator and which also serves to retain the shield in a stationary position after it has been brought to rest.

A still further object of this invention is 40 to provide an improved shield which is so constructed as to provide means for supporting the rifles and other paraphernalia of the occupants, when it is being moved from place to place, so that the latter will 45 be entirely free to manipulate the shield, the said means also serving to carry any of the occupants that may become injured or in any way disabled during the engagement.

Various other objects and advantages will 50 become apparent during the continuance of the following description.

The above and other objects which will 55 become apparent, are accomplished by such means as are shown in their preferred form in the accompanying drawings, described in the following specification and then more

specifically pointed out in the appended claims.

In the accompanying drawings wherein like characters designate like parts throughout the several views;

Figure 1 is a rear elevation of my improved shield shown in its preferred embodiment.

Fig. 2 is a sectional view of the shield 65 taken on line 2—2 of Fig. 1.

Fig. 3 is a sectional view taken on line 3—3 of Fig. 1.

Fig. 4 is a fragmentary view of an improved support that is used in connection 70 with the preferred embodiment of my invention.

Fig. 5 is a perspective view of a bracket that is used.

Fig. 6 is a rear elevation of my invention 75 showing the same in a slightly modified form.

Fig. 7 is a sectional view of my invention taken on line 7—7 of Fig. 6.

Fig. 8 is a detail view showing an im- 80 proved bracket.

Fig. 9 is a similar view.

Fig. 10 is another detail view.

Fig. 11 is a view in elevation showing the 85 hinged tampion.

Referring now to Figs. 1 to 5 inclusive, wherein is illustrated my invention in its preferred embodiment, the plates 10 and 11 constitute the body portion of my improved shield, and have their adjacent longitudinal 90 edges fixed together as at 12 in order to assume a rigid position to each other. The plates 10 and 11 are preferably formed of heavy sheet steel or the like, so as to be capable of withstanding the terrific impact 95 of the missiles projected thereagainst. In the preferred embodiment of my invention, the plates 10 and 11 are preferably fixed together so as to extend at an approximately right angle to each other, as clearly shown 100 in Fig. 2 of the drawings. The advantageous features derived from this construction will be very fully set forth as the following description continues. Side plates 13 are fixed to the plates 10 and 11 adjacent 105 their respective extremities, so as to fully protect the occupants of the shield from the sides. The plates 13 are shown extending some distance rearwardly of the free ends of the plates 10 and 11 and while this construction of course, greatly adds to the protective- 110 ness of the shield, it is to be understood

that the dimensions of the plates may be varied consistently.

A pair of suitably curved brace members 14 and 15 serve to retain the plates 10 and 11 in a rigid position, the said brace members being arranged adjacent the ends of the plates and in close proximity to the side plates 13. Each of the brace members 14 and 15 respectively carry an upstanding hook portion 16 intermediate their upper and lower ends, which serve the purpose that will presently be described. Here it may be mentioned also that the plate 10 carries a series of hooks 17 adjacent its upper end, the end ones of the hooks 17 being arranged opposite the hooks 16 on the brace members 14 and 15 respectively.

Another brace member 18 connects the plates 10 and 11 intermediate their ends. 20 However this brace member is preferably made readily movable relative to the plates as will presently appear. The plate 10 carries a bracket 19 having an upstanding end 20 that receives a pin 21 carried adjacent 25 the lower end of the brace member 18. On the other hand the plate 11 has secured thereto a bracket 22 (shown in detail in Fig. 5) that carries an outwardly projecting stem 23 which projects through an opening in 30 the upper portion of the brace member 18. A cotter pin 24 is engaged with the stem 23 so as to normally retain the upper end of the brace member 18 thereon. However by 35 removing the cotter pin the brace member 18 can be disengaged from the stem 23 and swung backwardly, the pin 21 serving as the fulcrum. It will also be noted that the brace member 18 carries a hook 25 intermediate its upper and lower ends that is aligned 40 with one of the hooks 17 on the plate 10.

A bar 26 extends longitudinally of the plate 10 and is fixed thereto as shown at 27. The ends of the bar 26 project some distance beyond each end of the plate 10 and are 45 rounded so as to form axle sections 28. These axle sections are supported by wheels 29 which in turn serve to support the entire shield structure when being moved from place to place.

50 The plate 10 and the side plates 13 are provided with loop-holes 30 through which the occupants may fire. It is of course desirable to close the said loop holes at certain times and therefore I have devised 55 suitable mechanism for accomplishing this result. A pair of hinge brackets 31 are fixed in proximity to each of the loop holes and are designed to receive trunnions which are carried on a tampion 32. The tampion 60 32 also carries an upstanding lip 33 which, when in a closed position cooperates with a block 34, that is carried on a bracket 35 fixed to the adjacent plate. Consequently a fastening member 36 may be engaged with 65 the said block and lip to lock the tampion

securely in place. This form of closure means is especially desirable at the time the shield is being moved from place to place, under fire yet it is also equally useful when the occupants of the shield are reloading 70 their rifles. The tampion 32 will of course have to be formed of a very stout metal such for instance as sheet steel in order to effectually deflect the missiles which are projected thereagainst.

75 It is also desirable to provide improved means for facilitating the movement of the shield from place to place and to this end an improved handle is provided. With the view of forming the improved handle, a 80 pair of bars 37 are fixed to the plate 10 adjacent its lower edge as at 38, the said bars extending in a plane in parallelism with the plate 10 and terminating some distance below the lower edge thereof. At a suitable 85 point below the lower edge of the plate 10, the bars 37 are bent abruptly to form a pair of upstanding extensions 40 and incidently provide a pair of sharp shoulders 39. At their upper ends, the extensions 40 merge 90 into a connecting rod 41 that in turn carries the handle 42. From the foregoing it will be noted that when the shield is at rest, the entire weight will be subjected upon the bars 37 or more specifically upon the sharp 95 shoulders 39. Consequently by subjecting his weight upon the connecting rod 41 the operator may force the sharp shoulders of the bars 37 into the ground so as to assure the rigidity of the shield during the engagement. It is especially desirable to retain the shield in an approximately fixed position in view of the fact that the terrific impact of the missiles striking thereagainst would naturally tend to move the same to one side or 100 the other and thus create the liability of exposing the occupants. While the construction above set forth will under ordinary conditions serve to retain the shield in an approximately fixed position, or rather 110 against rearward movement, it is also desirable to retain the shield against forward movement at certain times. Otherwise the weight of the occupants resting upon the plate 10 would tend to move the shield to 115 some extent and thus not only cause the other occupants considerable annoyance but in some instances expose the occupants to the fire of the enemy. To this end retaining hooks 43 are pivotally connected to the 120 lower ends of the brace members 14 and 15 respectively, as at 44 so that by the exertion of the proper stress, the same may be securely fixed into the ground.

125 In connection with my improved shield I have also provided what may be termed as a support, the same being readily detachable whereby it may be used to carry the wounded or to support the same in connection with the shield during the engagement. 130

This support consists essentially of a pair of comparatively long poles 45 and 46 which are connected by a section of heavy fabric 47. The poles 45 and 46 carry a series of 5 rings 48 at their ends and intermediate portions, which engage the hooks 16, 17 and 25 respectively so as to support the same in the position illustrated in Fig. 2. When in this 10 position the support may be used for various purposes such for instance as retaining the ammunition or the rifles of the occupants or still, if the case may be, persons who have been wounded or disabled during the conflict. It is believed that this form of 15 support forms one of the important features of my improved shield inasmuch as its coöperation therewith is fully defined.

In concluding the description of the preferred embodiment of my invention, it may 20 be stated that any number of hooks 49 may be positioned on the inner face of the plate 11 so as to serve as supports for the paraphernalia usually employed in connection with devices of this character.

25 In Figs. 6 to 11 inclusive I have shown my invention in a slightly modified form or it may be stated, more plainly speaking, a simplified form. In this form plates 50 and 51 are fixed together as at 52 to extend in relation to each other similar to the plates 10 and 11. A bar 53 is fixed to the lower of the plates 50, the axle portions 54 thereof being supported by wheels 55. In this form the side plates 13 are eliminated, the brace 35 members 56 serving to retain the plates 50 and 51 in an approximately rigid position. Further, a pair of bars 57 and 58 are fixed to the lower plate 50 and project downwardly in a similar plane some distance below the lower edge thereof. At their lower ends, the bars 57 and 58 are bent upwardly to form a pair of extensions 59 and incidentally provide a sharp shoulder 60. The 40 extensions 59 may be connected by a cross rod 61.

The tampion which closes the loop-holes 62 is shown in detail in Fig. 11 and consists of a plate body portion 63 having a pair of trunnions 64 formed at one end for the reception in brackets 65 which are fixed to the plate 50 and a circular off-set 66 at an intermediate point, for the reception in the adjacent loop hole. The forward end of the plate 63 is upturned to form a flange 67 which, 45 when the tampion is in a closed position cooperates with a block 68 carried on the under bracket 69 which is fixed to the plate 50. When the brace assumes this position a fastening member 70 may engage with the flange 67 and the block 68 to retain the tampion in a secure position.

A pair of hooks 71 are fixed on the plate 51 and serve to support an ordinary spade 72. This implement is of course desirable, 55 yet it will be understood that it can be re-

placed with any other implement if it should be desired. It will be noted that the hooks 71 are shown in detail in Fig. 8.

In Fig. 9 I have shown in detail an improved bracket which consists of but a partly 70 screw-threaded stem 73 having a head portion 74 one end of which carries a ring 75. The shanks 73 of the brackets are positioned through suitable apertures 76 in the plate 50 and when screwed into a secure position the head portions 74 lie snugly against the face of the plate in Fig. 6. Suitable implements or other paraphernalia usually carried by soldiers may be retained in connection with the shield. 75

80 From the foregoing it is believed that the advantages and novel features of my invention will be readily understood and therefore further detailed description is deemed unnecessary. 85

It will be of course understood that I am not limited to either form of my invention as illustrated herein and that certain changes in the details of construction and in the arrangement of parts may be resorted to without departing from the spirit and scope of the invention as defined in the appended claims. 90

Having thus fully described my invention, what I desire to secure by Letters Pat- 95 ent is:—

1. In a shield of the character described, a pair of plates, said plates being connected to extend at right angles to each other, wheels supporting said plates, bars fixed to 100 the lower one of said plates, the lower ends of said bars extending below the lower edge of said lower plate, angular extensions formed at the lower ends of said bars and providing a sharp shoulder, and a handle 105 having connection with said extensions whereby said plates may be operated substantially as described.

2. In a shield of the character described, a pair of plates, said plates being connected 110 at an angle to each other, brace members connecting said plates, a bar extending longitudinally with respect to the lower plate, and fixed thereto for engagement with a pair of supporting wheels, bars fixed to the lower 115 one of said plates and projecting below the lower edge thereof, the lower end of said last mentioned bars being upturned to form a sharp shoulder, and a handle connecting said upturned portions, substantially as and for 120 the purpose specified.

3. In a shield of the character described, comprising a pair of protecting plates, means connecting said plates, means supporting said plates, the lower one of said 125 plates provided with a series of loop-holes, tampions pivotally mounted on said last mentioned plates adapted to close said loop-holes, bars fixed to said last mentioned plates and projecting below the lower edge thereof, 130

said bars being bent at a point below the lower edge of said last mentioned plates to provide a shoulder, a handle connecting said bars, and said shoulders adapted to engage with the ground to retain the shield in a stationary position.

4. In a shield including protecting plates, side plates connecting said first mentioned plates adjacent the ends thereof, wheels supporting said plates, a plurality of brace members connecting said first mentioned plates, a handle, means connecting said handle and the lower one of said first mentioned plates, and said means being adapted for engagement with the ground to retain the shield in a stationary position.

5. In a shield including protecting plates, side plates connecting said protecting plates, brace members connecting said first mentioned plates, wheels supporting said plates, depending hooks carried by said brace members adapted for engagement with the ground to retain the shield against forward movement, means carried by the lower one of said first mentioned plates, adapted for engagement with the ground to retain the shield against rearward movement, and a handle whereby the shield may be operated.

6. In a shield of the character described, a pair of plates forming the body portion thereof, said plates having connection and extending at an angle to one another, side plates connecting said first mentioned plates

adjacent their respective extremities, brace members connecting said first mentioned plates and arranged in close proximity to said side plates, another brace member pivotally connected to and mounted on the lower one of said plates, means connecting the upper end of said last mentioned brace member to the upper one of said plates, a support associated with said brace members and the lower one of said plates, said support extending approximately the entire length of the lower one of said plates, wheels for supporting said plates, and means to retain said plates against forward or rearward movement, substantially as and for the purpose set forth and described.

7. In a movable shield of the character described, a body portion, wheels supporting said body portion, bars fixed to said body portion and projecting below the lower edge thereof, the lower end of said bars being upturned to form a sharp shoulder, a handle connecting said upturned portions, said shoulders serving to bite into the ground and prevent the rearward movement of said body portion, as and for the purpose set forth and described.

In testimony whereof I affix my signature in presence of two witnesses.

MARTIN J. HAHRE.
